MAGNETICALLY CONTROLLED SWITCH

Filed Sept. 20, 1951

UNITED STATES PATENT OFFICE

2,666,112

MAGNETICALLY CONTROLLED SWITCH

Clarence L. Nelson, Minneapolis, Minn.

Application September 20, 1951, Serial No. 247,403

7 Claims. (CL. 200—87)

1

This invention relates to an electrical switch, and particularly to an electrical switch in which a movable contact is movable to positions into and out of engagement respectively with a fixed contact.

Such a type switch is now commonly used in the art, which switches embody a swinging member or lever having a handle member and having a movable contact secured thereto movable into position in engagement with a fixed contact by movement of said lever. The movement of said lever however is generally resiliently controlled by a spring or similar means. Such spring or other resilient means makes a more complicated structure and renders the switch somewhat noisy.

It is an object of this invention to provide a simple type of snap or throw switch having a frame, a fixed contact on said frame, a movable contact arranged to be moved into and out of engagement with said fixed contact, an oscillatable member mounted on said frame, a handle for oscillating said member, a magnet adjacent said fixed contact, and a member on said oscillatable member adapted to be attracted by said magnet to hold said oscillatable member in position with said contacts in engagement, said oscillating member being movable to a position with said movable contact spaced from said fixed contact.

It is another object of this invention to provide a switch comprising a frame, a fixed contact mounted on said frame, a movable contact adapted to be moved into and out of engagement with said fixed contact, a magnet adjacent said fixed contact, an oscillatable member mounted on said frame, a handle for oscillating said member, a second member carried on said oscillating member adapted to be attracted by said magnet so that in one position of said oscillating member said movable contact will be moved into engagement with said fixed contact and in another position of said oscillating member said second member will not be attracted by said magnet and said movable contact will be out of engagement with said fixed contact.

It is also an object of this invention to provide a switch comprising a frame having a plate-like top portion, a lever mounted intermediate its end on said top portion, a handle on said lever above said top portion, a movable contact on said lever below said top portion, a fixed contact on said frame, said movable contact being movable into engagement with said fixed contact by oscillation of said lever, a magnet on said frame adjacent

2

said fixed contact, a second magnet on said frame spaced from said fixed contact in the direction of movement of said lever, an armature carried by said lever below said top portion, and a cushioning means preferably being carried by said armature or magnets between said armature and magnets whereby a switch is provided which will be very quiet in operation and will not necessitate any springs or other resilient means for controlling the position of said lever.

It is still another object of this invention to provide a switch comprising a frame, a fixed contact mounted on said frame, a movable contact movable into and out of engagement with said fixed contact, a magnet disposed adjacent said fixed contact, an oscillating member on said frame, a handle for oscillating said member, a second member carried by said oscillating member and adapted to be attracted by said magnet so that in one position of said oscillating member said contacts will be in engagement and in another position of said oscillating member said contacts will be out of engagement.

These and other objects and advantages of the invention will be fully set forth in the following description made in connection with the accompanying drawings in which like reference characters refer to similar parts throughout the several views and in which—

Fig. 1 is a view in side elevation of said switch, a small portion being shown in vertical section, some parts being shown in different positions in dotted lines;

Fig. 2 is a vertical section taken substantially on line 2—2 of Fig. 1, as indicated by the arrows;

Fig. 3 is a substantially horizontal section taken on line 3—3 of Fig. 1, as indicated by the arrows;

Fig. 4 is a partial top plan view of said switch;

Fig. 5 is a view in side elevation of a modified form of said switch;

Fig. 6 is a vertical section taken substantially on line 6—6 of Fig. 5, as indicated by the arrows;

Fig. 7 is a vertical section taken on line 7—7 of Fig. 5, as indicated by the arrows;

Fig. 8 is a view in side elevation of a modified form of the device; and

Fig. 9 is a horizontal section taken on line 9—9 of Fig. 8.

Referring to the drawings, particularly Figs. 1 to 4, a switch is shown comprising a frame 10, and while this frame could be variously constructed, in the embodiment of the invention illustrated it is shown as comprising a plate-like top portion 10a and spaced portions 10b extending substantially

at right angles from portion 10a. Said frame 10 will preferably be made of material which is a non-conductor of electricity. Portion 10 has secured to its top side by screws 9 the usual plate 11 having portions projecting beyond portion 10a, the ends of which are offset upwardly and provided with openings 11a through which screws will pass to hold the switch in position on an outlet box or electrical outlet. Portion 10a and plate 11 are provided respectively with an aligned rectangular opening 10c and an aligned rectangular opening 11c. Plate 11 is provided at each side of opening 11c with upwardly and downwardly directed semi-cylindrical portions 11b and 11e which form a holding means for a pivot pin 12 which extends across portion 10a above the same. A lever 16 is mounted for oscillating movement on pin 12, said lever having secured thereto at its upper end a handle portion 16a disposed above portion 10a. Below portion 10a lever 16 has secured thereto a fixed contact 17 which is of yoke-like shape and has spaced side portions 17a. An armature 18 forming a permanent magnet is secured to contact 17, the same extending between the more adjacent side portions 17b thereof and being disposed centrally of contact 17, as shown in Figs. 1 and 3. A pair of fixed contact members 20 are secured to one member 10b and while these could be variously secured, they are shown as secured by headed rivets 21. Metal members 23 are shown engaging the opposite side of portion 10b than that engaged by contact members 20 which are also held by the rivets 21. Screws 24 are shown as threaded into members 23 and 10b and will act to hold conductors in engagement with members 23 and thus into electrical engagement with contact members 20. Contact members 20 will have their terminal portions 20a of somewhat concavo-convex form, as shown in Fig. 3. A permanent magnet 26 is secured to one portion 10b adjacent the fixed contacts 20. Portion 10b is provided with a lug engaged by said magnet so that said magnet will have its surface remote from portion 10b substantially parallel to the adjacent surface of armature 18. A second permanent magnet 28 is secured to the other portion 10b, said latter portion also having an inclined surface engaged with magnet 26 so that the surface of said magnet will be substantially parallel to the adjacent surface of armature 18 when the latter is adjacent magnet 28. Cushioning members 30 which may be made of felt, rubber or similar material, are disposed respectively between the armature 18 and the magnets 26 and 28. Said members 30 are shown as secured to the magnets 26 and 28 respectively.

In operation, the switch will be mounted in the usual manner on an electrical outlet. A cover plate is commonly placed over plate 11 and secured thereto. The handle 16a will project through the cover plate and can be conveniently engaged by the thumb or finger of the operator to move the same into the positions indicated in Fig. 1. When handle 16a and lever 16 are in the position shown in full lines in Fig. 1, the side portions 17a of the movable contact 17 will move between the fixed contacts 20 respectively and will move said contacts and their portions 20a somewhat apart. Portions 20a will thus be resiliently held in engagement with contact members 17 and the latter will in other words be wedged between the fixed contacts 20. When in said position the armature 18 will be strongly attracted by the magnet 26 and the switch will be held in its on position. Said lever 16 is very free-

ly movable and as the armature 18 nears magnet 26 it will be drawn towards said magnet. The member 30 will prevent any audible contact of armature 18 and magnet 26. When the switch is to be moved to off position, as shown in dotted lines in Fig. 1, the operator will again swing handle 16a. Armature 18 will now be swung adjacent magnet 28 and will be strongly attracted by said latter magnet. The switch will thus be held in its off position. Any audible engagement of armature 18 and magnet 28 will be prevented by the cushioning means 30. The switch is thus very easily moved from its on to its off position and is so movable without any audible sound. There is thus no clicking or snapping of any spring. The switch is nicely held in either of its two positions and will have to be moved by its handle 16a from one position to the other.

Referring to Figs. 5, 6 and 7, a modified form of the invention is shown. A frame 40 is shown having a top portion 40a of plate-like material and a portion 40b projecting at right angles from one end of portion 40a. In practice, portion 40a will preferably have an attaching plate, such as plate 11 shown in Figs. 1 and 4, attached thereto. A bearing 41 is provided in portion 40a in which is journaled a shaft 42 to the upper end of which is attached a knob handle 44. Handle 44 has a central hub which will engage one side of bearing 41, and the opposite side of said bearing is engaged by a gear 45 secured to shaft 42. Gear 45 meshes with a rack 46 slidable in guide members 47 secured to the underside of portion 40a by the rivets 48. When at one end of its movement, rack 46 will engage portion 40b, and a stop 40c is provided at one end of portion 40a forming a stop for said rack when moved in the opposite direction. A permanent magnet 50 is secured at the end of shaft 42 and said magnet as usual will have positive and negative poles.

A member 51 has a laterally extending lug 51a secured to portion 40b by the screw 52. Member 51 extends some distance from portion 40b substantially parallel to portion 40a and has secured thereto by the rivets 54 a permanent magnet 56. Member 51 is made of metal and the upper end portion 51b thereof constitutes a movable contact. Member 40 is preferably made of material which is a non-conductor of electricity. A member 57 has a laterally extending lug 57a extending toward one side of portion 40b and secured thereto by a headed screw 58. Screws 52 and 58 are provided with nuts 60 at the side of portion 40b opposite the lugs 51a and 57a, which nuts are tightened to engage portion 40b. Additional nuts 61 are threaded on the screws 52 and 58 and will act to hold conductors between the nuts 60 and 61. Screws 52 and 58 thus act as binding posts. Member 57 extends upwardly substantially to the free end of member 51 and has its upper end portion 57b bent at substantially right angles to extend transversely of member 51. Portion 57b of member 57 constitutes a fixed contact. The adjacent faces or surfaces of magnets 50 and 56 are at a slight angle and converge upwardly, as shown in Fig. 5. Magnet 56 will of course also have a positive and negative pole.

In operation when the positive pole of magnet 50 is opposite or at the corresponding end forming the negative pole of magnet 56, the magnets will attract each other and magnet 56 will move toward magnet 50 and carry with it the upper end of member 56 which will then engage the fixed contact formed by the end portion of member

57. The switch will then be in closed position. The magnets will be strongly attracted to each other and the switch will positively be held in this position. The adjacent faces of the magnets will be substantially parallel and in engagement. When the knob or handle 44 is turned through 180 degrees from said closed position, the positive poles of magnets 50 and 56 will be adjacent and opposite each other as will the negative poles. The magnets will then repel each other and magnet 56 will move away from magnet 50, as shown in Fig. 5, and the movable contact on member 51 will be separated from the fixed contact on member 57. The rack 46 will engage portions 40b and 49c respectively when the switch is in closed or open position and will indicate that the handle 44 has been turned the right amount.

The handle 44 will thus be turned to bring the switch to its on or closed position and to its off or open position. As the magnet 50 is rotated and its positive pole approaches the negative pole of magnet 56, the latter will be drawn to magnet 50 and magnet 50 will swing to a position so that the magnets are in horizontal alignment. As stated, magnet 56 moves the movable contact 51b into engagement with the fixed contact 57b. The switch is now in closed position and will be firmly held in said position by magnets 50 and 56. The switch will remain in its closed or open position until handle 44 is again turned. As in the structure shown in Figs. 1 to 4, there is no spring to snap from one position to another and the operation of the switch is entirely noiseless. The positions of the switch, as stated, will also be indicated by the rack 46 engaging the stops at either end thereof. A very efficient and simple switch is thus provided.

In Figs. 8 and 9 another modification of the device is shown. In these figures a plate 70 is shown to which is secured a plate 71 extending at right angles to plate 70. These parts correspond to the parts 40 and 49b of Fig. 5. Secured to member 71 is a contact member 73 which is identical with the contact member 57 shown in Fig. 5. Also secured to member 71 is a contact member 74 which is identical with the contact member 51 shown in Fig. 5. Member 74 carries a permanent magnet 75. The upper ends of members 73 and 74 will be the same as the upper ends of members 57 and 51 shown in Figs. 5 and 7. These upper ends are omitted in Fig. 8. A handle member 76 is swingable about the axis of a pivot 78 which will be secured to member 73 in any suitable manner. Handle 76 moves in a slot or opening in member 70 and has a substantially semi-circular portion 76a at the side thereof opposite its handle portion 76b. Portion 76a has formed thereon or secured thereto a gear segment 80. Gear segment 80 meshes with a small gear 81 secured to a shaft 82 journaled in a bearing member 83 which is in turn secured to member 70 by the screws or rivets 84. Shaft 82 is held from longitudinal movement in bearing 83 by pins 85. Shaft 82 has secured to its end a permanent magnet 86 which, as shown in Fig. 9, is arranged to be disposed in facial alignment with magnet 75.

In operation, when the positive pole of magnet 86 is opposite or at the corresponding end forming the negative pole of magnet 75, the magnets will attract each other and magnet 75 will move toward magnet 86 and carry with it the upper end of member 74 which will then engage the fixed contact formed by the end portion of member 73. The switch will then be in closed posi-

tion. The magnets will be strongly attracted to each other and the switch will positively be held in this position. The magnets will be moved to the stated position by the operator 5 swinging member 76 by taking hold of or pushing on handle portion 76b. The adjacent faces of the magnets will then be substantially parallel and in engagement. When the handle 76 is turned in the opposite direction, it will move gear 81 through substantially 180 degrees and the positive poles of magnets 75 and 86 will be adjacent each other as will the negative poles. The magnets will then repel each other and magnet 75 will move away from magnet 86 and the movable contact on member 74 will be separated from the fixed contact end of member 73. The ends of the segment 80 will engage member 70 and form a stop for the handle 76 when it has been turned to the right amount 10 to bring the magnets 75 and 86 to the desired position. The switch is thus easily moved to its on or closed position and to its off or open position. As the magnet 86 is rotated and its positive pole approaches the negative pole of magnet 75, the latter will be drawn to magnet 86 and magnet 86 will swing to a position so that the magnets are in facial alignment. As in the other forms of the device, there is no spring to snap from one position to another and produce a noise or click. The operation of the switch 15 is entirely noiseless. A very efficient and simple switch is thus provided.

From the above description it will be seen that I have produced a switch of simple construction and one that can be very easily and noiselessly operated. Even with the smallest switches the operation of spring pressed parts which snap into position causes quite a noticeable sound. At night when everything is quiet, such switches 20 are sometimes very annoying to people who are ill or nervous. As described, the switch of this invention is noiseless and yet can be very easily operated and is positively held in position. The device has been amply demonstrated in actual practice and found to be very successful and efficient.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. An electric switch having in combination, a frame, a fixed contact mounted on said frame, a lever pivoted intermediate its ends on said frame, a handle at one end of said lever, a movable contact carried adjacent the other end of said lever movable into engagement with said fixed contact and away from the same, an armature carried by said lever, a magnet adjacent said fixed contact and a magnet spaced from said fixed contact in the direction of movement of said lever, said lever being freely movable by said handle whereby when said movable contact is in position engaged with said fixed contact or in position spaced from said fixed contact it will be held in said positions respectively by said armature and the respective one of said magnets.
2. An electric switch having in combination, a frame having a top member, a lever pivoted to said frame, a handle on said lever at the top side of said top member, a movable contact on

said lever below said top portion, a fixed contact on said frame disposed to be engaged by said movable contact in one position of said lever, said movable contact being spaced from said fixed contact in another position of said lever, a magnet carried by said lever below said top portion, a second magnet on said frame adjacent said fixed contact, a third magnet on said frame spaced from said fixed contact in the direction of movement of said lever, and a cushioning means disposed between said first mentioned magnet and said second and third magnets, said lever being freely movable whereby said switch will operate quietly and will be held in positions with said movable contact engaged with said fixed contact or spaced therefrom by said magnets respectively.

3. An electric switch having in combination, a frame, spaced contact members of resilient material secured to said frame, a lever mounted on said frame for swinging movement, a movable contact on said lever with spaced portions adapted respectively to engage said fixed contacts and be resiliently engaged by said fixed contacts in one position of said lever, a handle on said lever, an armature on said lever between said spaced portions of said movable contact, a magnet on said frame adjacent said fixed contacts, a second magnet on said frame spaced from said fixed contact in the direction of movement of said lever, said lever being freely swingable whereby said movable contact will be held in position in engagement with said fixed contact or spaced from said fixed contact respectively by said respective magnets.

4. An electric switch having in combination, a frame, a lever mounted on said frame to swing to "on" and "off" position, a contact carried by said lever, a second contact disposed to be engaged by said contact when said lever is in said "on" position, a plate-like magnet carried by said lever with said first mentioned contact, a second plate-like magnet disposed adjacent said second contact, and a third plate-like magnet carried by said frame spaced from said second magnet, said first mentioned and second magnets being arranged to come into substantially parallel relation when said lever is in "on" position to hold said lever in position and said first mentioned and third magnets being arranged to come into substantially parallel relation when said lever is in "off" position to hold said lever in "off" position.

5. An electric switch having in combination, a frame, spaced resilient contacts mounted on

said frame, a lever pivoted intermediate its ends on said frame and movable to "on" and "off" positions, a handle at the outer end of said lever, the inner end of said lever comprising a bow-shaped member forming a contact and arranged to move with said lever to a position between and in engagement with said contacts, a substantially flat rectangular magnet having a groove thereabout, said magnet disposed in said member, a second magnet adjacent said contacts, and a third magnet spaced from said contacts whereby said first magnet is held in fixed position in engagement with said contacts or apart from the same.

10. A second magnet adjacent said contacts, and a third magnet spaced from said contacts whereby said first magnet is held in fixed position in engagement with said contacts or apart from the same.

15. An electric switch having in combination, a frame, spaced resilient contacts mounted on said frame, a lever pivoted intermediate its ends on said frame, a handle at the outer end of said lever, the inner end of said lever comprising a bow-shaped member, a substantially flat rectangular magnet having a groove thereabout and adapted to be disposed in said bow-shaped member, said bow adapted to move between and engage said contacts, a second magnet adjacent said contacts, and a third magnet spaced apart from said contacts whereby said member and first mentioned magnet are held in fixed position in engagement with said contacts or spaced apart from the same.

20. An electric switch having in combination, a frame, spaced resilient contacts extending inwardly of said frame, a lever pivoted in said frame having an outwardly extending handle, said lever having a bow-shaped frame and being movable to "on" and "off" positions, a magnet held in said bow-shaped frame, said magnet movable between said contacts and adapted to engage the same, a second magnet disposed adjacent said contacts and a magnet disposed apart

25. from said contacts, resilient cushion members secured to the adjacent surfaces of said second and third mentioned magnets whereby said frame and magnet can be held in fixed position between said contacts in its "on" position or apart from the same in its "off" position and said cushion members will make said switch noiseless.

CLARENCE L. NELSON.
